(57) **CLAIM**

The ornamental design for a cell phone protector case, as shown and described.

DESCRIPTION

FIG. 1 is a front perspective view of a cell phone protector case, showing my new design;

FIG. 2 is a rear perspective view thereof;

FIG. 3 is front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines indicate unclaimed portions of the article that form no part of the claimed design.
